VERTICALLY ADJUSTABLE TOP FOR FURNITURE

John J. Dombek, Chicago, Ill.

Application May 20, 1955, Serial No. 509,867

2 Claims. (Cl. 311—39)

This invention relates to an adjusting device, and more particularly to a height adjusting device for use with office desks, school desks, work tables, benches, typewriter and comptometer tables, cabinets and the like, and other similar articles, wherein it is desired to provide a supporting base having a table top or working surface adjustable thereto for raising and lowering, although other uses and purposes may be apparent to one skilled in the art.

According to the invention, a height adjusting device is provided in combination with a table supporting base and a table top for regulating the height of the table top or working surface. The adjusting device includes generally a plurality of screw rod members coacting with a plurality of nut members, wherein some of the members are directly connected to the supporting base while other members are directly connected to the table top. Driving means is provided for simultaneous or individual actuation of the screw rods or nuts, such as a manually operable crank.

In one embodiment, the adjusting mechanism includes a metal frame sandwiching a series of thin stamped metal gears. At the four corners of the frame, the gears are equipped with screw rods that raise and lower nuts carrying a strap-like frame on which the table top or bench top is secured. The gear frame is attached to the frame structure of the desk, table or bench. A crank is provided to be connected to one of the gears and rotation of this crank will drive all of the gears to uniformly actuate the screw rods for regulating the height of the table top.

Another modification provides a tilttable table top or bench top, wherein two separate gear trains will be used and driven independently. The screw rods will be pivotally connected to the table top and engageable with a rotatably driven nut.

Still another form of the invention provides that the screw rods are drivingly interconnected by a system of shafting and screw gearing.

Another form of the invention positions the screw rods horizontally for coaction with a toggle mechanism to raise and lower vertically guided table supporting plates.

Accordingly, it is an object of this invention to provide an adjusting device adapted to be used in combination with a stationary member and a movable member, wherein the relative positions between these members may be accurately adjusted.

Another object of this invention is to provide a height adjusting device in combination with a supporting base and a working surface, wherein the entire working surface may be uniformly raised or lowered.

A further object of this invention resides in the provision of a height adjusting device in combination with a table top and a supporting base, wherein the table top may be adjusted as to vertical as well as angular movement.

Another object of this invention is to provide an adjusting mechanism comprising a metal frame sandwiching a series of stamped thin metal gears secured to a stationary table base, wherein some of the gears are equipped

2

with screw rods that raise and lower nuts carrying a strap-like frame in which a table top or bench top is secured, and the rotation of one of the gears will drive all of them to uniformly actuate the screw rods.

- 5 Still another object of this invention resides in the provision of a height adjusting device in combination with a table supporting base and a table top comprising brackets which mount a plurality of screw rods that are drivingly interconnected by a system of shafting and screw gears, wherein nuts engaging with the screw rods are carried by a member secured to the table top and actuation of the shafting and gearing system varies the height of the table top.

Another object of this invention resides in the provision of a height adjusting device in combination with a table supporting base and a table top comprising vertically guided table top supporting plates drivingly interconnected with combination screw rod and toggle mechanisms for simultaneous raising and lowering of the table top supporting plates.

Other objects, features, and advantages of the invention will be apparent from the following detailed description of the drawings, which, by way of preferred examples only, illustrate the invention.

25 On the drawings:

Figure 1 is a broken plan view of a table equipped with a height adjusting device in accordance with the invention and showing some underlying parts in dotted view;

30 Figure 2 is an enlarged fragmentary sectional view, with parts in elevation, taken substantially along line II—II of Figure 1;

Figure 3 is an end elevation view of the embodiment shown in Figure 1, with parts broken away for clarity purposes;

35 Figure 4 is an enlarged detailed view of a portion of the height adjusting device shown in Figure 1;

Figure 5 is a reduced fragmentary perspective view of the height adjusting device removed from the table;

40 Figure 6 is a fragmentary broken view of a modified height adjusting device, with parts in elevation;

Figure 7 is a broken plan view of the height adjusting device of Figure 6, with parts broken away for clarification and showing some parts in dotted line view;

45 Figure 8 is a fragmentary end elevational view of a table equipped with another modified height adjusting device, with parts broken away and other parts in dotted line for clarification purposes;

Figure 9 is a perspective view of the height adjusting device shown in Figure 8, but being removed from the table;

50 Figure 10 is a perspective view of still another modified height adjusting device removed from a table for purposes of showing underlying parts, but being mountable on a table in the same manner as the modification shown in Figure 8;

Figure 11 is an enlarged fragmentary elevation view of a detailed portion of the mechanism illustrated in Figure 10; and

60 Figure 12 is an enlarged fragmentary sectional view, taken substantially along line XII—XII of Figure 10.

As shown on the drawings:

65 Referring generally to Figures 1—5, a height adjusting device, generally designated by the numeral 10, in accordance with the invention, is shown mounted in combination with a conventional table or bench which comprises a supporting base 11 and a table top 12.

The supporting base 11 includes four rectangularly positioned legs 13 held together by end connecting members 14, 14 and side connecting members 15, 15, the connecting members also serving as mounting members

for the height adjusting device as will be hereinafter explained.

The main frame of the height adjusting device 10 is generally U-shaped and comprises a pair of U-shaped plate members 16 and 17 having upwardly projecting flanges 16a and 17a, respectively, along their outer edges in close association to form a mounting plate for the frame and to maintain the plates 16 and 17 in properly aligned relationship to form a channel 18 accessible from the inside. The bight of the U-shaped frame constitutes the longest straight section of the frame and, in mounted relationship with the table supporting base 11, is fastened along the inside of a side connecting member 15, as seen in Figure 1, with suitable fastening means such as wood screws, while the legs of the U-shaped frame are fitted to co-extend along the major portion of the end connecting members 14, 14 to likewise be secured thereto by similar fastening means, such as wood screws.

To prevent the outside corners of the U-shaped frame at the intersection of the legs with the bight ends from hindering the mounting of the frame on the supporting base 11 and interfering with the corner connecting legs 13, a portion of the corner of the metal U-frame has been removed, as indicated by the numerals 19, 19 and seen most clearly in Figures 1 and 5.

A plurality of upstanding screw rods 20 are rotatably mounted along the U-shaped metal frame and carry a thin stamped metal gear 21 sandwiched between the plates 16 and 17 of the frame. In this instance, four screw rods are provided and rectangularly positioned at substantially the corners of the U-shaped frame. As shown most clearly in Figure 2, the screw rods 20 function as a shaft for the gears 21, and an inwardly depressed portion on each of the plates 16 and 17, as indicated by the numerals 16b and 17b, respectively, are provided to abut against the opposite sides of the hub of the gears 21 to maintain it in properly aligned position with respect to the frame. The screw rods 20 are additionally supported at their upper free ends by a bracket 16c extending upwardly from the flanges 16a of the lower plate member 16. The brackets 16c aid in maintaining the screw rods 20 in proper vertical alignment.

A plurality of intermeshing connecting gears 22 are sandwiched between the plates 16 and 17 of the U-shaped member along the legs and the bight, and in meshing engagement with the screw rod gears 21 to provide an interconnecting drive which effects synchronous operation of all of the screw rods 20 by the rotation of any one thereof. Each of the connecting gears 22 are also of thin stamped metal and are supported by vertically parallel shafts pivotally connected at either ends to the plates 16 and 17. One of the screw rods 20 is provided with a manually actuatable crank member indicated by the numeral 23, and which upon actuation will effect rotation of the screw rods 20 through the interconnect gear train.

Securely fastened to the underside of the table top 12 are a pair of strap members 24, 24. The strap members 24 are in parallel spaced relationship, each carrying a pair of nuts 25 along a portion which is spaced from the underside of the table top 12. The straps 24 and the nuts 25 are so positioned as to register with corresponding screw rods 20 in coaxing relationship thereto, so that upon actuation of the screw rods 20 through the crank 23 the height of the table 12 with respect to the supporting base or the surface on which it rests, may be varied. In other words, the height adjusting device 10 regulates the height of the table top 12, and due to the synchronously driven screw rods 20 engaging the nuts 25, substantially all points of the table top may be raised or lowered uniformly within the limits of the lengths of screw rods 20.

In the instant case, due to the number of intermeshing connecting gears 22 between the screw rod gears 21, a

clockwise rotation of the screw rod gear 21 connected to the crank 23 will effect a clockwise rotation of the other screw rod gears to uniformly raise and lower the table top 12 with respect to the supporting base 11.

Now referring to Figures 6 and 7, a modified height adjusting device is illustrated, wherein identical parts have been designated within the identical numbers as already used, especially in connection with the table on which the height adjusting device is mounted.

In this modification, the height adjusting device not only provides regulation of the height of the table top 12, but also is capable of tilting the table top to any desired amount within the limits of the height adjusting device.

The adjusting device of this modification comprises in general a pair of actuating shafts 30, 30 in spaced parallel relationship and mounted along the opposite end mounting and connecting boards 14. The shafts 30 are rotatably supported by spaced brackets or journal members 31 which extend inwardly from the end members 14 and are securely fastened thereto by suitable fastening means, such as bolts or wood screws, as indicated by the numerals 32.

The shafts 30 carry in locked relationship a screw gear 33 at each bracket 31 which meshes with a floating screw gear 34. The axis of each gear 34 is perpendicularly positioned with respect to the axis of the shaft mounted gears 33 and the former are bearingly guided by the terminal end portion of each bracket 31, as indicated by the numeral 31a.

The floating gears 34 are internally bored and threaded to mesh with corresponding threaded screw rods 35 which are vertically slidably and guided within the end portions 31a of each bracket 31.

Four screw rods 35 are provided, two of which are pivotally connected to the underside of the table top 12, as indicated by the numeral 36 (only one shown) along one side of the table top. Along the other side of the table top, the screw rods 35 are connected to the underside of the table top 12 by a swingable link 37 pivotally connected to a corresponding screw rod 35 at one end as indicated by the numeral 37a, and pivotally connected to the underside of the table top 12 at the other end as indicated by the numeral 37b. The swing link 37 allows for the tilting of the table top 12 upon manipulation of the actuating rod 30.

Projecting from one end of each actuating shaft 30 and through a suitable bore in the adjacent table leg 13 is a driving extension 38 terminating in a square end 38a. A suitable crank 39 is provided having a socket end 39a to be received over the square end 38a of the extension 38 in removable fashion for manual manipulation of the actuating rods 30. Thus by independent actuation of the actuating rods 30 the height of the table top 12 may be varied with respect to the supporting base 11 and the surface on which it may rest, or the table top may be tilted in any fashion, such as illustrated in Figure 6.

Now referring to Figures 8 and 9, another modified height adjusting device is illustrated in combination with the table supporting base 11 and table top 12.

In this embodiment, a pair of spaced mounting plates 40, 40 are securely fastened to the opposite end mounting boards 14, 14 of the supporting base 11.

Each mounting plate 40 carries an inwardly extending flange 41 along its bottom edge thereof, oppositely aligned vertical flanges 42, 42 projecting from the opposite vertical sides of the mounting plate 40 and adjacent the bottom flange 41, and a pair of horizontally positioned and longitudinally spaced top flanges 43, 43 projecting inwardly from the top edge of the mounting plate 40.

Between each top flange 43 and the lower flange 41 is mounted a rotatable screw rod 44 which carries adjacent its bottom end a screw gear 45, all screw gears 45 being in substantially the same horizontal plane. An actuating

shaft 46 extends perpendicular to the screw rods 44 and has its ends mounted in the oppositely facing side flanges 42. A pair of screw gears 47 are secured in axially spaced relationship along the actuating shaft 46 to be in intermeshing engagement with the screw rod screw gears 45.

An inverted U-shaped member 48 has its bight portion fastened to the underside of the table top 12, and its legs support at the free ends nuts 49 on outwardly extending portions 50. The strap members 48 are carried through their nuts 49 on the corresponding screw rods 44, and it will be noted that the legs of the strap member 48 are positioned within the spaced top flanges 43 of the mounting plate 40.

To effect a drive on the actuating shafts 46, an extension 51 projects from one end of the shaft and terminates in a substantially square end to receive a complementally formed socketed crank 52, as seen in Figure 8. To effect synchronous movement of the screw rods 44 in each mounting plate 40, a connecting shaft 53 is provided which has its ends mounted in the opposite side plates 40 adjacent corresponding screw rods, and carries screw gears 54, 54 which intermesh with screw gears 55, 55 secured to the corresponding screw rods 44 near the top thereof, and as clearly shown in Figure 9.

Thus, manipulation of the crank 52 will effect synchronous driving of all of the screw rods 44 in the adjusting device to uniformly elevate or lower the table top 12 in adjusting the height thereof.

Now referring to Figures 10, 11 and 12, still another modified height adjusting device is illustrated to be mounted in combination with a table supporting base and a table top in substantially the same manner as the modification of Figures 8 and 9.

In this embodiment a pair of spaced mounting plates 60, 60 are securely fastened to the opposite end mounting boards, such as the plates 40, 40 are attached to the mounting boards 14, 14 as illustrated in Figure 8.

The vertical edges of each mounting plate 60 are inwardly bent to define oppositely facing guide slots 61, 61 for receiving therein in slidable relationship a table top supporting member 62. Each supporting member 62 carries a horizontal flange 62a along its upper edge for fastening to a table top in a similar manner as are the strap members 48 secured to the table top 12 as shown in Figure 8.

Each table top supporting member 62 is raised and lowered by a combination screw rod and toggle mechanism comprising in general a screw rod 63 rotatably supported by the mounting plate 60, and a toggle mechanism 64 attached to the vertically slidable supporting member 62. Each screw rod 63 is rotatably journaled at opposite ends by a pair of ears 65, 65 extending inwardly from the opposite vertical edges of the mounting plate 60 and adjacent the upper edge thereof. A bearing hanger 66 is suitably attached to the mounting plate 60 for supporting a reduced diametral section 63a of screw rod 63. The bearing hanger also functions as a thrust bearing in prohibiting axial movement of a screw rod. The movable table top supporting member 62 is vertically slotted, as indicated by the numeral 67, in the area of the bearing hanger 66 to permit vertical movement of the plate 62.

At either side of the bearing hanger 66, the screw rod 63 includes oppositely threaded portions 63d and 63c which respectively engage oppositely and internally threaded blocks or nuts 68 and 69 of the toggle mechanism 64. A pair of pivotally connected links 70 and 71 are pivotally secured to the table top supporting member 62 as indicated by the numeral 72. The opposite free ends of links 70 and 71 are respectively pivotally attached to screw nuts 68 and 69, respectively.

To assure simultaneous coaxing vertical movement of each table top supporting member 62, a spur gear train drivingly interconnects each screw rod 63 and includes a series of intermeshing thin stamped metal gears 73 ex-

tending between the screw rods and sandwiched between a pair of spaced supporting plates 74. The supporting plates 74 are suitably fastened at opposite ends to gears 65 of mounting plate 60. It is noted that one of the gears 73 at each end of the gear train is suitably fastened to the adjacent end of the corresponding screw rod 63.

To effect a drive on the screw rods 63, an extension is provided from one of the screw rods terminating in a substantially square end to receive the complementally formed socketed crank 75, as noted in Figure 10. Thus, manual rotation of the crank 75 effects axial movement of screw nuts 68 and 69 in opposite directions along the corresponding screw rod 63 to shorten the distance between the screw rod and the pivotal toggle link connection 72 and effect upward movement of the table top supporting member 62. The toggle mechanism 64 and the supporting member 62 will then take the position as indicated in dotted lines in Figure 10.

Thus, manipulation of the crank 75 will effect synchronous driving of all of the screw rods 63 in the height adjusting device to uniformly elevate or lower a table top connected to the supporting member 62 in adjusting the height thereof.

It will be understood that modifications and variations may be effected without departing from the scope of the novel concepts of the present invention, but it is understood that this application is to be limited only by the scope of the appended claims.

I claim as my invention:

1. In combination with a table top and supporting base, an adjusting device for varying the height of the table top which comprises a pair of elongated supporting plate members secured to opposite sides of the supporting base, each plate member having a plurality of upstanding screw rods paralleling each other and said plate, laterally extending flanges for rotatably supporting said rods, an actuating shaft extending perpendicular to said rods, oppositely positioned lateral flanges for rotatably mounting said shaft, gears on said shaft and rods in intermeshing relationship, a U-shaped strap having its bight secured to the underside of the table top and provided with laterally extending flanges on the free ends of the legs thereof, nuts carried by said flanges being in coaxing relationship with said screw rods, a connecting shaft having its opposite ends supported by said plate members, a gear on said connecting shaft, a gear on one screw rod of each plate member meshing with the connecting shaft gears, and means for driving one of the actuating shafts.

2. A vertically adjustable table comprising, a supporting base with a pair of elongated supporting plate members secured to opposite sides of the supporting base, each plate member having a pair of vertical screw rods at opposite ends paralleling each other and said plate, laterally extending flanges for rotatably supporting said rods to permit rotation about the respective rod axes while precluding translation relative to said plate members, an actuating shaft between and perpendicular to each rod of a said pair, oppositely positioned lateral flanges for rotatably mounting said shaft to permit rotation about its axis but preclude translation relative to said plate members, gears on said shafts and rods in intermeshing relationship, a U-shaped strap having its bight secured to the underside of the table top and provided with laterally extending flanges on the free ends of the legs thereof, nuts carried by said flanges threadably surrounding said screw rods, a connecting shaft having its opposite ends supported by said plate members to permit rotation about its axis but preclude translation relative to said plate members, a gear on each end of said connecting shaft, a gear on one screw rod of each plate member meshing with the connecting shaft gears, and means for driving one of the actuating shafts.
